UNITED STATES PATENT OFFICE.

WILLARD S. PAIN AND FREDERICK L. WOOD, OF MERIDEN, CONNECTICUT, ASSIGNEES
TO AEOLIAN COMPANY, OF NEW YORK, N. Y., A CORPORATION OF CONNECTICUT.

MUSIC-SPPOOL HEAD.

1,016,229.

Specification of Letters Patent.

Patented Jan. 30, 1912.

Application filed May 2, 1911. Serial No. 624,551.

To all whom it may concern:

Be it known that we, WILLARD S. PAIN and FREDERICK L. Wood, citizens of the United States, and residents of Meriden, in the county of New Haven and State of Connecticut, have invented certain new and useful Improvements in Music-Spool Heads, of which the following is a specification.

This invention relates to new and useful improvements in music spool heads and the object of our invention is to provide a new and improved head for spools on which perforated music sheets are wound, such as are used in mechanically playing musical instruments, which spool heads are simple in construction, strong and durable, handsome in appearance, and easily applied.

In the accompanying drawings in which like letters of reference indicate like parts in all the figures: Figure 1 is a face view of one of our new and improved music spool heads. Fig. 2 is a longitudinal sectional view of the same. Fig. 3 is a sectional view on the line $c-a$ of Fig. 2. Fig. 4 is a longitudinal sectional view of a music spool provided with our improved heads, parts being broken away.

A sheet metal disk 1 is struck with a circumferential flange 2 on one face and a central neck 3 on the opposite face. A struck up sheet metal cup 4 is provided in its rim with an upwardly extending flange 5 which fits against the inner face of the rim flange 2 of the disk 1 and the said flange 2 is then folded over inward over the flange 5 of the cup to form the rim head 6 on the outer face of the head, whereby the disk 1 and cup 4 is provided in its raised central portion with an exterior circular recess 7 of sufficient depth and of such shape or configuration as to receive the end of a bearing pivot or clutch between which the roll is held and rotated when in use in conventional manner. A tube 9 is inserted through the neck 3 until its inner end rests against the inner surface of the cup 4 and its outer end projects some distance, greater or less, beyond the neck 3, and this tube is held securely in place by punching tongues 10 out of the neck and tube and pressing them inward. The free ends of the tubes 9 are inserted in the open

ends of a barrel 11, preferably made of pasteboard. One head is securely held in place in the end of the barrel 11 by a pin 12 passed through the spool and the inserted 55 end of the tube 9. The other head is made adjustable lengthwise of the barrel and is held by a pin 13 passed through the barrel and through longitudinal slots 14 in the inserted tube 9, and the free end part of this 60 tube is slotted lengthwise as at 15 and slightly spread to form spring fingers which serve to hold the adjustable head at its various adjustments.

Having described our invention what we 65 claim as new and desire to secure by Letters Patent is:—

1. In a music spool head, the combination with a disk, of a cup held on the same, said cup having means for engaging a spool bearing and a tube projecting beyond the outer face of the disk, the inner end of said tube resting against the inner surface of the cup, substantially as set forth. 70

2. In a music spool head, the combination with a disk, of a cup held on the same, said cup having means for engaging a spool bearing and a neck projecting from the outer face of the disk and a tube held on and projecting outwardly beyond said neck, 80 substantially as set forth. 75

3. In a music spool head, the combination with a disk, of a cup held on the same, said cup having means for engaging a spool bearing and a neck projecting from the outer face of the disk and a tube held on and projecting outwardly beyond said neck, 85 the inner end of said tube resting against the inner surface of said cup, substantially as set forth. 90

4. In a music spool head, the combination with a disk, of a cup held on the same, said cup having means for engaging a spool bearing and a neck projecting from the outer face of the disk and a tube held on and projecting outwardly beyond said neck, 95 and inwardly projecting parts punched through the neck and tube, substantially as set forth.

5. In a music spool head, the combination with a disk, of a cup held on the same, said cup having means for engaging a spool

bearing and a neck projecting from the outer face of the disk and a tube held on and projecting outwardly beyond said neck, the inner end of said tube resting against the inner surface of said cup, and inwardly projecting parts punched through the neck and tube, substantially as set forth.

Signed at Meriden in the county of New Haven and State of Connecticut.

WILLARD S. PAIN.
FREDERICK L. WOOD.
